3 Claims. (Cl. 253—69)

This invention comprises improvements in or relating to axial-flow fluid machines, such as, for example, axial-flow compressors and turbines of gas-turbine engines.

This invention has for an object to provide a construction of axial-flow fluid machine in which difficulties experienced with known multi-stage machines due to distortion and relative thermal expansion are avoided.

According to the present invention, a multi-stage axial-flow fluid machine comprises rotor means including a plurality of axially-spaced rows of rotor blades; and a stator structure enclosing the rotor means and comprising a main casing, and a plurality of axially-spaced rows of stator blades or vanes, there being one row of said stator blades or vanes just upstream of each row of said rotor blades, the stator blades being provided at their radially-outer ends with platforms to form parts of the wall of the working fluid annulus of the machine around the stator blades or vanes, each said platform being supported from the main casing, and the platforms of adjacent rows of said stator blades or vanes having aligned axial extensions which together afford an annular stator shroud encircling the tips of the row of rotor blades intermediate the adjacent rows of stator blades or vanes. By 'aligned' is meant that the extensions of adjacent rows of stator blades have parts at substantially the same radial distance from the axis of rotation of the rotor means, which thus co-operate to afford said shroud.

Heretofore it has been the practice to provide an annular shroud of substantially the same axial dimension as the rotor blades, which encircles the rotor blades and is formed in a small number of arcuate pieces, say six, with such an arrangement not only are difficulties experienced in design in order to allow for thermal expansion but it has been found that these pieces are liable to distortion in operation of the machine. These difficulties are avoided by the construction of the present invention.

The invention is applicable both to machines whereof the rotor blades have integral shrouds at their tips, and to machines whereof the rotor blades are not provided with integral shrouds.

According to a preferred feature of the invention, the rotor blades have integral tip shrouds, the axial extensions of the platforms at the radially-outer ends of the stator blades are radially offset from the radially-inner surfaces of the platforms, thereby to provide a channel into which the integral tip shrouds of rotor blades extend, and the integral tip shrouds are arranged to co-operate with the axial extensions of the platforms to provide gas seals to prevent excessive flow of working fluid around the tips of the rotor blades. In the preferred arrangement the integral tip shrouds have on their outer surfaces axially-spaced ribs which have radial surfaces, and there are provided radial surfaces on the axial extensions of the vanes, which have for gas sealing purposes small axial clearances from the radial surfaces on the axially-spaced ribs, all other clearances between the tip shrouds

2

and the axial extensions being substantially greater than said small axial clearances.

One embodiment of this invention will now be described with reference to the accompanying drawing, which shows in axial section part of an axial-flow multi-stage turbine.

The turbine comprises three rows of rotor blades 10, 11, 12 mounted at the peripheries of corresponding rotor discs, and a stator structure including a main casing 13 and three rows of nozzle guide vanes 14, 15, 16, the rows of guide vanes 14, 15, 16 being respectively just upstream of the rows of the rotor blades 10, 11, 12.

The guide vanes have both inner and outer blade platforms 14a, 14b; 15a, 15b; 16a, 16b, and the inner blade platforms 14a, 15a, 16a of each row are secured rigidly together in annular assembly by suitable structure. The outer blade platforms 14b, 15b, 16b of each row are free from one another.

The high-pressure nozzle guide vanes 14 have their outer platforms 14b fixed axially and circumferentially with respect to the casing 13 but left free radially. For this purpose, the casing 13 is provided outside the rotor blades 10 with a radially-inwardly-projecting annular rib 17 formed with an inwardly-facing annular channel 18, and the blade platforms 14b are provided along their downstream edges with axial extensions 19 which terminate at their downstream edges in radial flanges 20 engaging in the channel 18 to locate the guide vanes axially and which also provide, as described below, a portion of the stationary shrouding for the rotor blades 10. The guide vanes 14 are located circumferentially by radial locating pegs 21 mounted in the casing and engaging recesses in bosses 22 on the platforms 14b.

The shrouding for the rotor blades 10 is formed partly by the extensions 19 and partly by axial extensions 23 on the upstream edges of the blade platforms 15b of the intermediate nozzle guide vanes 15, the extensions 19 and 23 meeting with slight clearance and being radially offset from the inner surfaces of the platforms 14b, 15b to provide a channel 23a receiving tip shrouds 24 on the blades 10. The radially inner surfaces of the axial extensions 19, are shaped to afford a pair of radial plane surfaces 19a which in operation of the machine have axial clearances from corresponding radial surfaces 25 on axially-spaced radially outwardly-extending ribs 26 formed on the outer surfaces of the tip shrouds 24 such as to provide gas seals limiting the flow of working fluid around the tip shrouds.

The vanes 15, 16 are located in the casing 13 in similar ways. Thus each vane 15, 16 has on its platform 15b, or 16b adjacent its upstream and downstream edges hooked formations 27, 28, 29, 30 which engage respectively in axially-facing annular channels 31, 32, 33, 34, the channels being formed respectively in the radial rib 17 and three further ribs 35, 36, 37 provided internally of the casing 13. The platforms 15b, 16b are thus located radially. The ribs 17, 35, 36 and 37 are also provided with radially-inwardly-projecting dogs 38 co-operating with dogs 39 on the platforms 15b, 16b to locate them circumferentially. The platforms 15b are also located axially by axially extending ring members 40, 41 extending toward each other between the ribs 35, 36 and abutting radial flanges 42 on axial extensions 43 of the platforms 15b, and the platforms 16b are located axially by means of flanges 30a at their rearward ends being trapped between the rib 37 and a ring 50.

The blades 11 have tip shrouds 24 and stator shrouding for these rotor blades is provided in a manner similar to that described for the blades 10, by the axial extensions 43 of the platforms 15b and axially-aligned co-operating extensions 44 on the upstream edges of the

platforms 16b, the extensions 43 being shaped to afford plane radial surfaces 24 which have clearances from plane surfaces 25 on ribs 26 such as to afford gas seals to prevent excessive leakage of gas around the tip shrouds 24.

It will be seen that the platforms 14b, 15b, 16b of the guide vanes are spaced radially from the casing 13 and cooling air is fed into this space from between the casing 13 and the nozzle discharge chutes leading from the flame tubes of the gas turbine engine to the high-pressure nozzle guide vanes 14. The air passes through the ribs 17, 35 and 36 by means of drillings 45, 46, 47, therein and also through cut-away portions on the hooked formations 28 and 29, and through drillings 48 in ring member 40. The air passes into the working fluid channel through the small clearances between the platforms 14b, 15b and 16b.

We claim:

1. A multistage axial-flow fluid machine comprising rotor means including axially-spaced first and second rows of rotor blades and a stator structure enclosing the rotor means which stator structure comprises a main casing having internally thereof a series of axially-spaced inwardly-projecting circumferential ribs, a first row of guide vanes upstream of said first row of rotor blades, a second row of guide vanes in flow series between said first and second rows of rotor blades, each of said guide vanes having an inner platform and an outer platform, means rigidly securing the inner platforms of the first row of guide vanes together in annular assembly, means rigidly securing the inner platforms of the second row of guide vanes together in annular assembly, each of the outer platforms of the first row of guide vanes having an axial downstream extension projecting downstream therefrom axially part way over the outer ends of the first row of rotor blades and at the downstream end of said downstream extension a radial flange, one of said ribs of the main casing having an inwardly-facing annular channel engaged by said radial flanges to locate the first row of guide vanes axially in the casing and also having a downstream-facing annular channel, means locating the first row of guide vanes circumferentially in the main casing, each of the outer platforms of the second row of guide vanes having an axial upstream extension projecting upstream therefrom axially part way over the outer ends of the first row of rotor blades and terminating adjacent the downstream ends of said downstream extensions of the first row of guide vanes, each of the outer platforms of the second row of guide vanes also having radially outwardly-projecting hooked formations adjacent both its upstream edge and its downstream edge, the hooked formations adjacent the upstream edges engaging said downstream-facing annular channel of said one rib, a second of said ribs of the main casing having a downstream-facing annular channel engaged by said hooked formations adjacent the downstream edges of the outer platforms, said outer platforms of the second row of guide vanes and one of said ribs also having interengaging dogs locating these guide vanes circumferentially in the casing, and each of said outer platforms of the second row of guide vanes having at their downstream edges radially-

5 outwardly projecting flanges, and a pair of ring members, one on each of the upstream and downstream sides of the radially outwardly projecting flanges, each of said ring members axially abutting by one end the radially-

10 outwardly projecting flanges and by the other end said main casing to locate the second row of guide vanes axially in the main casing.

2. A multi-stage axial-flow fluid machine according to claim 1, comprising a third row of guide vanes downstream of said second row of rotor blades, which guide vanes have inner and outer platforms, means rigidly securing the inner platforms of the third row of guide vanes together in annular assembly, each outer platform of the third row of guide vanes having at its upstream and downstream edges radially outwardly projecting hooked formations, a third of said ribs and a fourth of said ribs each having a downstream-facing annular channel engaged respectively by the hooked formations at the upstream edges of the platforms and the hooked formations at the downstream edges of the platforms, means maintaining said hooked formations in the annular channels, and interengaging dogs on said ribs and the outer platforms of the third row of guide vanes to locate them circumferentially on the main casing, downstream axial extensions of the outer platforms of the second row guide vanes axially projecting part way over the second row of rotor blades, and upstream axial extensions of the outer platforms of the third row guide vanes projecting axially upstream and terminating adjacent the downstream edge of the downstream axial extensions of the second row guide vanes.

3. A multi-stage axial-flow fluid machine according to claim 2, wherein said first and second rows of rotor blades have integral tip shrouds at their outer ends, the tip shrouds having axially-spaced radially outwardly projecting ribs which have at their outer ends upstream-facing radial surfaces, wherein said axial downstream extensions of the outer platforms of the first and second rows of guide vanes and the axial upstream extensions of the outer platforms of the second and third rows of guide vanes are radially offset outwardly from the inner surfaces of the outer platforms to form channels receiving the tip shrouds of the rotor blades, and wherein the axial downstream extensions have each a pair of axially-spaced downstream-facing radial surfaces having small axial clearance from the upstream facing radial surfaces of the ribs on the tip shrouds to provide gas seals, the remaining portions of the tip shrouds having a substantially greater clearance from the stator structure than said small axial clearance.
